UNITED STATES PATENT OFFICE.

WALTER H. TOMLINSON, OF CHICAGO, ILLINOIS.

DOUGHNUT-MACHINE.

1,320,662.

Specification of Letters Patent.

Patented Nov. 4, 1919.

Application filed March 15, 1918, Serial No. 222,544. Renewed August 14, 1919. Serial No. 317,584.

To all whom it may concern:

Be it known that I, WALTER H. TOMLINSON, a citizen of the United States, residing at Chicago, county of Cook, State of Illinois, have invented a certain new and useful Improvement in Doughnut-Machines, and declare the following to be a full, clear, and exact description of the same, such as will enable others skilled in the art to which it pertains to make and use the same, reference being had to the accompanying drawings, which form a part of this specification.

Doughnuts, in order that they may be properly fried, must be kept in the grease a predetermined length of time and, as they are light enough to float, must be turned over so as to permit both sides to become browned.

The object of the present invention is to produce a simple and novel machine by means of which doughnuts or the like may be kept in a bath of hot grease for a predetermined length of time, be automatically turned over and, after a further predetermined length of time, be automatically removed from the grease.

The various features of novelty whereby my invention is characterized will herein-after be pointed out with particularity in the claims; but, for a full understanding of my invention and of its object and advantages, reference may be had to the following detailed description taken in connection with the accompanying drawing, wherein:

Figure 1 is a side elevation of a machine arranged in accordance with my invention, the vat or tank for containing the grease being shown in section;

Fig. 2 is a section taken approximately on line 2—2 of Fig. 1;

Fig. 3 is a top plan view on an enlarged scale of a fragment of the conveyer; and

Fig. 4 is a section on a still larger scale on a plane extending longitudinally of the conveyer and at right angles to the plane thereof.

Referring to the drawing, 1 represents a vat or tank of any suitable size and shape adapted to be heated in any suitable way as, for example, by means of one or more burners, 2, lying underneath the same. A skeleton framework, indicated as a whole at 3, is constructed and arranged to be set detachably into the vat or tank; the framework

being of approximately the same dimensions as the vat or tank so as to fill the latter.

On the frame, 3, are two endless belt conveyers, 4 and 5. The conveyer 4 is arranged at one end of the frame, and the conveyer 5 at the other end. The main portion of each conveyer lies in two separated horizontal planes while the end of the conveyer 4 adjacent to the conveyer 5 is inclined upwardly so as to overlie one end of the latter 65 conveyer. The other end of the conveyer 5 is also inclined upwardly so as to bring the upper portion thereof above the top of the corresponding end of the tank or vat.

It will be seen that if the tank or vat is filled with hot grease to a level slightly above the upper halves of the horizontal portions of the conveyers, the conveyers are driven in the same direction, so that the upper halves are moving toward the right hand end in Fig. 1; doughnuts may be laid upon the left hand end of the conveyer 4 and be carried slowly through the hot grease until they are nicely browned on the under side, whereupon they will ride up the incline at 80 the center of the vat or tank and be dropped onto the left hand end of the conveyer 5; each doughnut being turned over in its passage from one conveyer to the other so that when the half fried doughnuts reach the 85 conveyer 5, the undone parts are on the under side and the browned parts are faced upwardly; the doughnuts being carried slowly by the conveyer 5 through the hot grease until they are completely fried and then being carried upon the incline at the right hand end of the apparatus where they will be discharged into a waiting receptacle which may be placed there to receive them.

The conveyers may take any suitable 95 form. In the arrangement shown, each consists of a series of transverse slats, 6, hinged together by means of suitable hinges, 7. At intervals on each conveyer there may be placed upwardly projecting vanes or partitions, 8, which will prevent the doughnuts from being crowded together if the level of the grease should be so high as to float the doughnuts above the conveyers.

The horizontal portions of the conveyers 105 may be kept in proper alignment in any suitable way. Thus, horizontal tracks, 9, may be provided for engaging the edges of the upper halves of the horizontal portions of the conveyers from underneath and simi- 110

lar tracks, 10, may be provided for overlying the lower halves of the horizontal portions of the conveyers. The conveyers preferably run over rollers extending the entire 5 width thereof; there being rollers, 11 and 12, at the ends of the horizontal portion of the conveyer 4 and there being rollers, 13 and 14, at the ends of the horizontal portions of the conveyer 5. The inclination of 10 the right hand ends of the conveyer devices is secured by passing the conveyer 4 over a roller, 15, lying to the right of the roller 12 and near the top of the frame, while the conveyer 5 is passed over a roller, 16, lying 15 to the right of the roller 14 and above the top of the frame.

In order to take the driving strain from 20 the slatted conveyers and secure a positive coöordinated movement of the two conveyers, assuming of course that suitable provision 25 is made for simultaneously driving at least one of the rollers associated with each conveyer, each conveyer is preferably edged at opposite sides with a sprocket chain, 17, which sprocket chains pass over suitable sprocket wheels, 18, on the ends of the various rollers.

If desired, the extreme left hand end of 30 the conveyer 4 may be inclined upwardly and passed around a roller, 19, which nominally lies above the grease level; this roller being provided with adjusting means, 20, by means of which slack in the conveyer may be taken up.

35 If desired, the doughnuts may be delivered to the apparatus by means of a suitable endless conveyer, 21, which passes over a roller, 22, extending transversely across the left hand end of the conveyer 4. By 40 driving the member 21 in the same direction as the conveyers 4 and 5 it will be seen that doughnuts, 23, may be placed on the former at any suitable point and be carried to and deposited upon the conveyer 4.

45 Any suitable means may be provided for driving the conveyers. In the arrangement shown, there is a sprocket chain drive, 24.

While I have illustrated and described

with particularity only a single preferred form of my invention, I do not desire to 50 be limited to the exact structural details thus illustrated and described; but intend to cover all forms and arrangements which come within the terms employed in the definitions of my invention constituting the ap- 55 pended claims.

I claim:

1. In an apparatus of the character described, a receptacle for hot grease, mechanism for turning doughnuts or the like over 60 after they have been in said receptacle for a predetermined length of time, and mechanism for thereafter removing them after a further predetermined length of time.

2. In an apparatus of the character described, a receptacle for hot grease, means in one end of the receptacle for carrying doughnuts or the like through that end of the receptacle and then removing them therefrom, and means in the other end of 70 the receptacle for carrying the doughnuts or the like through that end and delivering them to the aforesaid means in an over-turned condition.

3. In an apparatus of the character described, a receptacle for hot grease, two endless conveyers arranged one in each end of said receptacle, one of said conveyers being caused to travel upwardly in the vicinity of the other conveyer so as to overlie that 80 end of the latter conveyer.

4. In an apparatus of the character described, a receptacle for hot grease, two endless conveyers arranged one in each end of said receptacle, one of said conveyers being caused to travel upwardly in the vicinity of the other conveyer so as to overlie that end of the latter conveyer, and the latter conveyer being caused to travel upwardly in the vicinity of the end of the receptacle to bring it above the top of the receptacle. 85 90

In testimony whereof, I sign this specification.

WALTER H. TOMLINSON.
